UNITED STATES PATENT OFFICE

160,694

CONDIMENT SHAKER

Henry H. Crimmel, Hartford City, Ind.

Application October 27, 1949, Serial No. 5,725

Term of patent 14 years

(Cl. D44—22)

To all whom it may concern:

Be it known that I, Henry H. Crimmel, a citizen of the United States, residing at Hartford City, State of Indiana, have invented a new, original, and ornamental Design for a Condiment Shaker, of which the following is a specification, reference being had to the accompanying drawing, forming a part hereof.

I claim:

The ornamental design for a condiment shaker, as shown.

HENRY H. CRIMMEL.
